CONICAL SCANNING ANTENNA

Julius Halpern, Brookline, Mass., and Norman F. Ramsey, Santa Fe, N. Mex., assignors, by mesne assignments, to the United States of America as represented by the Secretary of War

Application September 6, 1945, Serial No. 614,726

3 Claims. (Cl. 250—33.65)

1

This invention relates in general to antenna systems, and more particularly to such systems embodying an eccentric rotating beam of electromagnetic energy.

In certain types of radio object-locating systems, a directional receiving antenna has a radiation pattern which is made to point in a direction which is a few degrees different from the direction of the antenna axis. The antenna is rotated, which causes this eccentrically-pointing beam to rotate in synchronism with it. This scanning of space by a rotating eccentric beam is called conical scanning, because of the shape of the pattern of revolution made by the axis of the antenna beam.

All directional antenna patterns, however, have directions other than that of the main beam of smaller amounts of radiation. These side lobes in the radiation pattern, as they are called, are usually at an angle of a few degrees from the axis of the main beam, and are touching the main beam. These side lobes are undesirable in that they, as well as the main beam, will receive signals, and the apparent direction of the energy received by the antenna at any instant will be somewhat ambiguous. A detailed explanation of conical scanning is given in application Serial No. 531,826, filed April 19, 1944, by Leland J. Haworth and Edward M. Purcell, entitled "Communication System." Hereafter the term "radiation pattern" will mean the variation in sensitivity of the receiving antenna with angle from the antenna axis.

Among the objects of the present invention, therefore, are:

1. To provide an antenna adaptable to conical scanning.

2. To provide such an antenna whereby the abovementioned undesirable effects of the side lobes of the antenna pattern are lessened.

In accordance with the present invention there is provided an antenna system in which the axis of the portion of the side lobes nearest the axis of revolution of the antenna at any time is made to be in substantially the same direction as the angle of the axis of the main lobe when it is diametrically opposite to its position at this time.

This invention will best be understood by reference to the drawings, in which:

Fig. 1 shows one type of antenna system which may be used in accordance with the present invention, and

Fig. 2 is a diagram of the present radiation pattern.

Referring now to a description of the appa-

10 ratus and to Fig. 1, there is shown a functional diagram of one type of antenna system which could be used to obtain the radiation pattern of this invention. A circular wave guide 10 has energy fed into it from a radio-frequency transmitter, noted but not shown. In front of the open end 11 of the wave guide is a metallic reflector 12 and an insulating cup-shaped housing 13. Paraboloidal reflector 14 is mounted in such a manner that metallic reflector 12 is substantially at the focal point of the paraboloid. Motor 15 is mechanically coupled to wave guide 10, and causes the wave guide to rotate about its own axis, thus rotating components 12 and 13 also. In one embodiment, a reflector 14 also rotates in accordance with the turning of wave guide 10. In another embodiment the reflector 14 is not physically connected to the guide 10, and so does not rotate.

20 Referring now to the operation of the system, and to Fig. 1, electromagnetic energy is fed into wave guide 10 from the transmitter, not shown. Electromagnetic waves are sprayed out of the open end 11 of the wave guide 10 and are reflected back toward paraboloid 14 by metallic reflector 12. Insulating material 13 is such that it allows electromagnetic radiation to readily pass through it. The waves are then reflected from paraboloid 14 towards the right of the figure.

30 The type of antenna system described and illustrated herein has a highly directional radiation pattern. If components 10 and 12 are mounted in a symmetrical manner with respect to the reflector 14, the axis of the directional beam will lie substantially along the axis of wave guide 10. In the present system, however, the positioning of the components is asymmetrical, and the beam of the system will point in a direction that is a few degrees displaced from the direction of the axis of wave guide 10. Furthermore, as the guide 10 is rotated, this eccentric beam will rotate also, its axis describing a cone-like surface in space.

40 45 Refer now to Fig. 2. The axis of wave guide 10 is represented by center line 20. In one position of rotation of guide 10, the main beam of the radiation pattern will be in a position such as 21, with its axis being represented by center line 22. The major side lobes of beam 21 are lobes 23 and 24. A rotation of 180° of wave guide 10 will cause the main beam of the radiation pattern to be in a position 25, with its axis being represented by center line 26. The pattern for this position of the wave guide 10 is

shown in dotted lines. The major side lobes are shown as lobes 27 and 28.

In the present invention, the dimensions of paraboloidal reflector 14 and the amount of asymmetry of components 10 and 12 are carefully chosen so that the side lobe 23 of the main lobe 21 closest to the axis of revolution 20 will have its axis lying along substantially the same line as the axis of the main lobe when it is in position 25, this being diametrically opposite to position 21 of the main lobe. Thus the angle between the major axis of the main lobe and the major axis of a side lobe will be equal to the apex angle of the conical surface described by the major axis of the main lobe. Or in other words, the cone described by the major axis of the main lobe is tangent to the cone described by the major axis of the side lobe.

That this procedure will reduce the ambiguity normally resulting from large side lobes can readily be seen. It must first be pointed out, however, that the purpose of a conical scanning radiation pattern is to compare the amplitude of the two signals received by two such lobes as 21 and 25 and so to determine the direction of the object causing the echo. It is seen that when the antenna is pointing towards the echo, the beams 21 and 25 each receive the same amount of energy. Let us assume that the side lobes are not positioned with respect to the main lobe in the manner mentioned above, and let the axis of one side lobe of beam 21 be represented by center line 29. Furthermore, let the radio echo be coming from a direction such as 29. At this angle, it is seen that the side lobe of beam 21 will receive as much energy as the main lobe 25. Thus while the antenna is rotating there will be no change in the amplitude of the received signal while the main beam is in position 21 over that while the main beam is in position 25, and it would be assumed that the radio echo is coming from the direction of axis 20, instead of its actual direction, that of axis 29.

However, if the side lobe 23 of main lobe 21 is in the direction along the axis of beam 25, this ambiguity will be done away with. The main lobe 25 will give a very much stronger echo than side lobe 23, and there will be no question of the fact that the radio echo lies along the axis of revolution 20.

It is the angle of eccentricity of the axis of the paraboloidal reflector with respect to the axis of the guide 10 which determine the angular swing of the main lobe. In practice, this angle is varied and the radiation pattern is taken at each angle. The angle used practically is the one which gives the radiation pattern according to Fig. 2.

This arrangement permits a relatively wide angle scan with the central cross-over point of the radiation pattern much nearer the source of radiation than in conical scanning systems heretofore used.

While there has been described what is at present considered the preferred embodiment of the invention it will be obvious to those skilled in the art that various changes and modifications may be made therein without departing from the invention, and it is, therefore, desired to claim all such changes and modifications as fall within the true spirit and scope of the invention.

10 We claim:

1. An antenna comprising a wave guide adapted to transfer electromagnetic energy, a paraboloidal reflector asymmetrically disposed about said wave guide, said wave guide passing through 15 said reflector, a metallic reflector juxtaposed to one end of said wave guide and disposed substantially at the focal point of said paraboloidal reflector, and means for rotating said wave guide, whereby a beam of energy having a main lobe and at least one adjacent minor side lobe 20 will be radiated, said wave guide and said paraboloidal reflector having an amount of asymmetry that upon rotation of said wave guide the angle between the major axis of said main lobe 25 and the major axis of said side lobe adjacent thereto will be equal to the apex angle of the 25 conical path described by the major axis of said main lobe.

2. The antenna of claim 1, further including 30 an insulating cup-shaped housing mounted at the end of said wave guide facing said metallic reflector and serving to connect said metallic reflector to said wave guide, said metallic reflector being a disc.

3. An antenna comprising an electromagnetic energy transmission element, a reflector asymmetrically disposed about said element, said reflector and element radiating electromagnetic energy in the form of a beam having a main lobe 40 and at least one adjacent minor side lobe, and means coupled to said antenna for rotating said beam so that the major axes of said main lobe and said minor side lobe of said beam describe a pair of conical surfaces, the said element and reflector having an amount of asymmetry that said conical surfaces are tangent to one another.
